ANCHOR

Thomas R. Gardiner, Piedmont, Calif.

Application November 4, 1946, Serial No. 707,556

5 Claims. (Cl. 114—208)

1

The present invention relates to anchors, and more particularly to anchors of the twin fluke type. The present invention is an improvement in part over my prior patent for "Stop Device For Anchor Shanks" granted August 30, 1949.

An object of the invention is to provide a twin fluke anchor of strong and sturdy construction having greater holding power for its size.

A further object of the invention is to provide a twin fluke anchor having an improved pivot for the shank of the anchor, so arranged as to increase the strength of the anchor and hold the twin flukes in proper spaced relation.

Another object of the invention resides in the provision of an improved crown for a twin fluke anchor which furnishes a relatively long bearing stop for the shank and accurately determines the fluke angle between the plane of the fluke blades and the shank axis.

Still a further object of the invention is to provide a crown for a twin fluke anchor which is so shaped and arranged with respect to the shank pivot and the center of area of the fluke blades as to offer very little resistance to burial of the blades, and to produce an initial downward and forward tilt of the blades on the bottom or ground which will insure positive burial of the blades upon the exertion of sufficient pulling force on the shank.

Several forms which the invention may assume are exemplified in the following description and illustrated by way of example in the accompanying drawings, in which:

Fig. 1 is a top plan view of one form of twin fluke anchor embodying the invention.

Fig. 2 is a longitudinal section taken generally along the line 2—2 of Fig. 1.

Fig. 3 is a partial cross-section taken generally along the line 3—3 of Fig. 1.

Fig. 4 is a fragmentary top plan view of a modified form of the invention.

Fig. 5 is a partial longitudinal section of still another form of the invention.

In the form of the invention disclosed in Figs. 1 to 3, inclusive, a pair of flukes 10, 10 are provided whose blades 11 are laterally spaced on offset and lie in a common plane and have rounded forward ends 12 and sharpened edges 13 diverging in a rearward direction toward the outer side edges 14 of the blades. There are flanges or arms 15 integral with blades 11, said arm projecting from the top and bottom faces of the blades. If desired, the flanges or arms 15 may project from only one face. Flanges or arms 15 are integrally joined to one another by a U-

2

shaped member 16 whose arms 17 extend between the rear blade tabs 18 and 19, and whose base 20 holds the arms in spaced relation.

The arms 17 of the U-shaped member 16 are generally parallel to one another but as shown the flanges 15 themselves diverge slightly in a forward direction beginning from the points of attachment 15a or integration of the flanges with the blades themselves. The divergent flange portions 15 are bevelled, tapering towards the blade faces in a forward direction, with their front ends merging into the blades in the region of the rounded ends or corners 12.

A pivot pin 21 extends through aligned holes 15 22 in the parallel flange arms 17, the ends of the pin being slotted to fit snugly over the rear tabs 18, 19 on the blades. It is to be noted that the inner edges 23 of the tabs are spaced from the arms 17 to permit placing of the holes in the plane of the blades 11. One slot 24 of the pivot pin is substantially longer than the other slot 25, to permit its assembly in the manner to be described hereinafter. The pin 21 is suitably secured, as by welding, to the blade tabs 18, 19.

25 A shank 26 is mounted on the pivot pin 21 and has a hole 27, or some other suitable means, at its forward end for the attachment of a cable (not shown). This shank is swingable in a plane at right angles to the plane of the blades 11 between predetermined limits. A stop for the shank is provided by a generally diamond-shaped crown 28. As shown in the drawings, the crown may be made of one piece, bent to fit over the top and bottom faces of the flukes 10 with a rear fold 29 integrating the rear sides 30 of the crown. The forward sides 31 of the crown are bifurcated to provide a space 32 through which the shank 26 may move during its pivotal movement on the pin 21 and into which the flanges 15 may extend.

35 Similarly, the rear sides 30 and fold 29 of the crown are slotted, as at 33, to provide space for the arms 17 and base 20 of the U-shaped member 16. The crown 28 may be attached to the flukes 10 in any suitable manner, as by welding the fold 29 to the tabs 18, 19 and the forward ends 35 of the forward sides 31 to the blades 11.

The crown 28 is so disposed with respect to the pivot pin 21 and the shank 26 as to provide a stop between the inner surface of each rear side 30 of the crown and the top and bottom surfaces 50 of the shank. The angle that the axis of the shank 26 makes with the plane of the fluke blades 11 is determined by engagement of the shank with either rear side 30 of the crown. This angle 55 may be accurately fixed since the shank makes a

relatively long bearing contact with each rearward side of the crown, as is evident from Fig. 2. It is to be noted that this angle is the same as the angle of inclination of the rear crown sides to the plane of the flukes.

It is also to be noted that the top and bottom pivot points 34, where the forward and rear sides 30, 31 of the crown merge, and which may rest on the ground, are forward of the pivot pin 21, and between the pivot pin and the center of area of the flukes 10. This arrangement insures an initial forward and downward tilt of the fluke blades 11 against the ground, in order that the pull taken on the shank 26 will increase the angle of tilt of the blades to the ground and cause them to dig in and bury themselves to the maximum extent. Thus, the diamond shape of the crown not only provides such initial forward tilt, but also provides a stop for the shank 26. The fact that the merging point or line 34 between the forward and rearward sides 30, 31 of the crown is relatively narrow insures that the initial pivoting or tilt of the blades will occur and also insures the maximum burial of the blades since the crown offers very little resistance to such burial.

It has been pointed out above that one of the pin slots 25 is substantially longer than the other pin slot 24 to facilitate assembly of the device. When such assembly takes place, one of the rear tabs 18 of the fluke blades is bent from its normal plane to permit insertion of the pin 21 through the hole 22 in one arm 17 of the flange, through the shank 26, and through the other arm 17 of the flange, placing the long slot 25 over the opposing tab 19 on the other fluke blade. The extended length of this slot 19 permits the pin to be moved inwardly until the other short slotted end of the pin is free of the plane of movement of the inner edge 23 of the tab 18. The tab 18 may then be bent back to its initial position coincident with the plane of the fluke blade, whereupon the pin 21 may be slid back to position the short slot 24 over the repositioned tab 18. Thereafter, the pin may be secured, as by welding, to both tabs, offering support for the tabs and also insuring the appropriate spacing of the fluke blades 11. The pin 21 assists in resisting any tendency for the flukes 10 to alter the angle of divergence between the flanges 15.

In the embodiment of invention disclosed in Fig. 4, the fluke blades 11 are separate from one another, in view of the omission of the U-shaped rearward flange portion 16 shown in Fig. 1. The blades are held in proper divergent position and in proper spaced relation by the pin 21a itself, whose slots may be of equal length, since it can be assembled in place without difficulty. Following its insertion through the flange arms 17a and shank 26, and with the proper position of its slotted ends over the rear tabs 18, 19 of the blades, the pin 21a may be securely welded to the tabs. In addition, the blades 11 may be held against movement with respect to one another by the welding of the crown fold 29 to the tabs.

In the form of invention illustrated in Fig. 5, the rear sides 30a of the crown merge smoothly into the back 29a of the crown, which is disposed over the base 20a of the flange. The pivot pin 21 and the rear end of the shank 26 are disposed adjacent the base 20a in order that an extended surface contact may still be obtained between the top and bottom of the shank and the rear sides 30a of the crown. This design and disposition of the crown 28, shank 26 and pin 21 obviate the

necessity for providing a space in the rear of the crown for the base and arm portions of the flange, as in the Figs. 1 to 3 embodiment.

The blades 11 are relatively wide compared to their length to avoid the necessity for attaching a stock to their rearward portion. By making the blades of such comparative great width, the anchor is stabilized without the inclusion of a stock, insuring that both flukes 10 will engage the ground or bottom upon dropping of the anchor overboard. Moreover, the relatively large width with respect to the length provides a large fluke area to give the anchor greater holding power. It may also be pointed out that the increase of the width with respect to the length of the blades brings the center of the fluke blade area closer to the point of pivoting of the shank on the pin 21 or 21a, making the anchor much stronger since there is less tendency for the blades 11 to bend as they are pulled into the ground by the pulling force exerted on the shank 26.

It is, therefore, apparent that a strong and sturdy anchor of relatively great holding power for its size has been provided. The crown arrangement not only provides for the initial tilt of the blades into the ground, but also pre-determines the fluke angle between the shank 26 and the blades 11 by engagement of the shank with one side 30 of the crown 28.

While I have shown preferred forms of my invention, it is to be understood that various changes may be made in their construction by those skilled in the art without departing from the spirit of the invention as defined in the appended claims.

Having thus described my invention, what I claim and desire to secure by Letters Patent is:

1. An anchor comprising a pair of fluke blades lying generally in a common plane, a pair of arms at the rear of said blades integral with each other and with said blades, a pin extending through said arms and having slotted ends fitting over said blades and secured thereto, the slot in one pin end being substantially longer than the slot in the other end, and a shank pivotally mounted on said pin between said arms and blades.

2. In an anchor of the type comprising spaced flukes lying generally in a common plane and a shank pivotally mounted therebetween adjacent the rear edges of the flukes for movement in a plane perpendicular to the plane of the flukes, the improvement which comprises a crown constituting a separate element from the flukes and shank but fixed to the flukes, said

55 crown being of generally diamond shape, having a base portion embracing the rear edges of the flukes and having legs extending forwardly from the base portion on opposite sides of the flukes and in symmetrical relation thereto, said legs constituting a combined stop member for the shank and a brace or reinforcement member for the flukes, and comprising rear portions diverging forwardly from the base portion to provide said stop member and front portions converging forwardly from the rear portions and terminating at their forward ends adjacent the flukes, said front portions being bifurcated to allow passage of the shank.

60 3. In an anchor of the type comprising spaced flukes lying generally in a common plane and a shank pivotally mounted therebetween adjacent the rear edges of the flukes for movement in a plane perpendicular to the plane of the flukes, the improvement which comprises a con-

65 70 75

tinuous, U-shaped flange fixed to and disposed along adjacent edges of the flukes and having a base at the rear edges of said flukes, and a crown constituting a separate element from the flukes and shank but fixed to the flukes, said crown being of generally diamond shape, having a base portion which embraces the rear edges of the flukes and is bifurcated to allow passage of the base of said flange and having legs extending forwardly from the base portion on opposite sides of the flukes and in symmetrical relation thereto, said legs constituting a combined stop member for the shank and a brace or reinforcement member for the flukes, and comprising rear portions diverging forwardly from the base portion to provide said stop member and front portions converging forwardly from the rear portions and terminating at their forward ends adjacent the flukes, said front portions being bifurcated to allow passage of the shank.

4. In an anchor of the type comprising spaced flukes lying generally in a common plane and a shank pivotally mounted therebetween adjacent the rear edges of the flukes for movement in a plane perpendicular to the plane of the flukes, the improvement which comprises flange members fixed to and lying along adjacent edges of the flukes, a pivot pin passing through said flanges at the rear end thereof and mounting said shank, and a crown constituting a separate element from the flukes and shank but fixed to the flukes, said crown being of generally diamond shape, having a base portion embracing the rear edges of the flukes and having legs extending forwardly from the base portion on opposite sides of the flukes and in symmetrical relation

10
15

thereto, said legs constituting a combined stop member for the shank and a brace or reinforcement member for the flukes, and comprising rear portions diverging forwardly from the base portion to provide said stop member and front portions converging forwardly from the rear portions and terminating at their forward ends adjacent the flukes, said front portions being bifurcated to allow passage of the shank.

5. An anchor comprising: a pair of fluke blades lying generally in a common plane and being laterally spaced from each other; spaced arms secured to the inner edges of said blades and being joined to one another at one pair of ends; a pin extending through said arms adjacent the juncture thereof; the ends of said pin being slotted and receiving and being secured to the ends of the blades adjacent the juncture of the arms; and a shank pivotally mounted on said pin between said arms and blades.
